United States Patent Office

Des. 224,362
Patented July 18, 1972

224,362

BOAT

William H. Wilson, Fort Smith, Ark., assignor to Rebel
Boat Company, Inc., Fort Smith, Ark.

Filed Dec. 28, 1970, Ser. No. 26,660

Term of patent 14 years

Int. Cl. D12—06

U.S. Cl. D71—1

FIG. 1 is a perspective view of a boat embodying my design viewed from the rear and starboard side.

FIG. 2 is a perspective view thereof from the forward and port side.

FIG. 3 is a plan view thereof.

FIG. 4 is a side elevational view thereof.

FIG. 5 is a rear elevational view thereof.

I claim:

The ornamental design for a boat, as shown and described.
